UNITED STATES PATENT OFFICE.

OBED CHARLES HAWKES, OF BIRMINGHAM, COUNTY OF WARWICK,
ENGLAND.

DESIGN FOR BEVELED GLASS.

SPECIFICATION forming part of Design No. 18,695, dated October 23, 1888.

Application filed July 11, 1888. Serial No. 279,669. Term of patent 14 years.

To all whom it may concern:

Be it known that I, OBED CHARLES HAWKES, a subject of the Queen of Great Britain, residing at Birmingham, in the county of Warwick, England, have invented and produced a new and original Design for Beveled Glass, of which the following is a specification, reference being had to the accompanying drawings, forming part thereof.

5 The leading feature of my design for beveled glass is a bead on the bevel thereof.

Figure 1 represents a section of a piece of beveled glass embodying my invention. Fig. 2 represents a face view thereof.

15 In the drawings, A represents a piece of glass having on its face a beveled rim, a, and

beads b on said rim. At the inner edge of the rim is shown a channel, c; but the said channel does not constitute an essential feature of my design, and may be omitted from the drawings.

I claim—

The design for beveled glass herein set forth, the same consisting of a beveled rim portion with a bead thereon, substantially as shown 25 and described.

OBED CHARLES HAWKES.
